UNITED STATES PATENT OFFICE.

HERBERT N. BRENEMAN, OF MILWAUKEE, WISCONSIN.

SUPPORT FOR RAZOR-STROPS.

No. 925,747.

Specification of Letters Patent. Patented June 22, 1909.

Application filed May 8, 1908. Serial No. 431,638.

To all whom it may concern:

Be it known that I, HERBERT N. BRENEMAN, a citizen of the United States, residing at Milwaukee, county of Milwaukee, and 5 State of Wisconsin, have invented new and useful Improvements in Supports for Razor-Strops, of which the following is a specification.

My invention relates to improvements in 10 supports for razor strops and straps of other flexible material, such as emery cloth, etc., used for sharpening edged tools.

The object of my invention is to provide 15 means for supporting articles of the described class at any desired tension, the supporting frame being collapsible and the strap of leather or other abrasive material may be reversed in position by detaching the same at one end and connecting it to another 20 part of the frame in a different position of adjustment.

In the following description reference is had to the accompanying drawings in which the figure is a perspective view of a device 25 embodying my invention.

Two rectangular frames A and B are centrally pivoted together at C, the lower ends D and E being adapted to rest upon a table or other suitable support and the upper ends 30 of the frames being connected by a flexible strap or band F, which is preferably permanently secured to metallic hooked end members G and G', which are adapted to engage the upper ends of the frames. The 35 strap F holds the frames in a raised position, as illustrated in the drawings, by connecting their upper ends and holding them at a distance from each other less than the total length of the two frames as measured from 40 the pivoted points to their respective ends.

To reverse the strap as to bring the under side uppermost, it is unhooked from the frame at one end and swung pivotally around the remaining connected end and attached to one of the foot pieces D (or E). 45 For example, the hook G may be detached and the strap swung around the upper end of the frame B until the hook G can be engaged with the cross piece E of the frame A, whereupon it will extend from D to E and the cross pieces E and D thereupon become 50 the foot pieces of the frame in the new position of adjustment. The under side of the strap F, illustrated in the drawings, will 55 then be uppermost in the new position of adjustment. When the frame is to be folded

for transportation, the strap F may be unhooked at one or both ends, whereupon the frames are permitted to collapse to a horizontal position. The cross pieces are preferably 60 covered with a sheathing of rubber or other suitable material, but this covering is not essential to my invention.

The frames A and B are preferably each composed of a single piece of wire bent into 65 the desired shape. Strands of wire composing the frame A may be coiled at the center, as illustrated in the drawings, and the strands composing the frame B may be offset and passed through these coils to form 70 the desired pivotal connection. In use, the tension upon the band F may be increased to any desired degree by pressing downwardly upon the connected frames at any point. The operator will grasp one of the 75 frames, either above or below the pivot point C or by taking hold of one of the hooked end members G or G', thus steadyng the frame, while the blade to be sharpened is reciprocated upon the band.

The term "band" is used in its generic sense to include a strop, a strap of emery cloth or any equivalent material used for sharpening edged tools.

Having thus described my invention what 85 I claim as new and desire to secure by Letters Patent is,

1. In a device of the described class, the combination of two crossed pivoted frames and a flexible band having an upper surface 90 of material adapted for sharpening edged tools, connecting their upper ends said band being of nearly the same length as that of the frames and adapted to permit the frames to approach more nearly to a horizontal 95 than to a vertical position when connected by the band.

2. In a device of the described class, the combination of two crossed pivoted frames and a flexible band, having an upper surface 100 of material adapted for sharpening edged tools, provided with hooks at its respective ends engaging one end of each frame and supporting the connected ends of said frames in raised positions.

3. In a device of the described class, the combination of two crossed pivoted frames and a flexible band, having an upper surface 110 of material adapted for sharpening edged tools, provided with hooks at its respective ends engaging one end of each frame and supporting the connected ends of said frames

2
in raised positions, each of said hooks being detachable and adapted to engage any one of the frame ends.

4. In a device of the described class, the combination of two crossed pivoted frames and a flexible band, connecting their upper ends, said frames being composed of wire strands with the strands of one frame coiled at the center of the frame and the strands of

the other frame offset through said coils ¹⁰ to form a pivotal connection between the frames.

In testimony whereof I affix my signature in the presence of two witnesses.

HERBERT N. BRENEMAN.
